UNITED STATES PATENT OFFICE.

SAM F. KLOHS, OF LARKINS, FLORIDA, ASSIGNOR TO CAMEL COMPANY, OF CHICAGO,
ILLINOIS, A CORPORATION OF ILLINOIS.

STARTING AND CLOSING MEANS FOR DOORS.

Application filed November 24, 1924. Serial No. 751,777.

This invention relates to a supplemental side door for railway cars.

Railway box cars for certain purposes, as for example in transporting automobiles and the like, must have door openings of wider extent than is usually afforded by the usual sliding door. For this purpose, supplemental doors are usually provided to increase the door opening. As a rule, these supplemental doors are usually provided with a jamb or post at their front edge. This jamb is adapted to be anchored to the floor of the car so that the supplemental door may serve as a part of the car wall when the car is used for purposes not necessitating an increased door opening. In the past it has been more or less difficult to operate these supplemental doors especially in bringing them to closed position and starting them from their closed position. Further in the prior constructions, there was always more or less looseness, and not sufficient rigidity to make a durable and tight construction adapted for hauling finely divided lading.

It is an object of this invention to overcome such defects, and this is accomplished in the provision of a supplementary car door equipped with means for bringing or assisting in bringing the same to a tight closed position and for starting or assisting in starting the same when it is being opened, and which is rigidly secured to tightly close the door opening without weakening the car structure.

It is a further object of this invention to provide a construction in which the supplemental door is automatically drawn inwardly by novel means as it is being closed, and in which the door is automatically locked or unlocked by the operation of the closing and starting means.

It is also an object of this invention to generally improve the structure of such supplemental doors and the operation and securing thereof whereby all the advantages of the supplemental door are retained without sacrificing any of the advantages or uses of such a box car.

With these and other objects in view which will become more apparent in the following description and disclosures, this invention comprises the novel structure and combinations of parts hereinafter described

and more particularly pointed out and defined in the appended claims.

In the accompanying drawings which illustrate a preferred embodiment of this invention and in which similar reference numerals refer to similar features in the different views:

Figure 1 is a fragmentary view in side elevation of a box car showing the main and supplemental doors in closed position.

Figure 2 is a sectional view upon the line 2—2 of Figure 1.

Figure 3 is an enlarged fragmentary interior elevational view of the supplementary door, the full lines indicating the mechanism in its locked position and the dotted lines in its unlocked position; the side plate of the car being shown in section.

Figure 4 is an enlarged fragmentary interior elevational view of the supplementary car door, the full lines showing the combined locking and operating mechanism in its locked position and the dotted lines illustrating it in its unlocked position, the floor of the car being shown in section.

Figure 5 is an enlarged and broken rear end elevational view of the supplemental door showing the adjacent car parts in section, with parts omitted.

Figure 6 is an enlarged fragmentary interior elevational view of the jamb on the supplemental door.

Figure 7 is an enlarged end elevational view of the structure shown in Figure 6.

Figure 8 is an enlarged fragmentary interior elevational view of the lower portion of the supplementary car door.

Figure 9 is a sectional view taken on the line 9—9 of Figure 8.

Figure 10 is a plan view of the upper locking plate.

Figure 11 is a plan view of the lower locking or rack plate.

As shown on the drawings:

Referring now to the drawings which illustrate one embodiment of this invention, it will be observed that there is shown in Figures 1 and 2 an ordinary box car provided with an extended or enlarged door opening which is closed by a main sliding door 1 and a supplemental sliding door 2. These doors may be of any standard construction and may be hung in any approved manner.

The rear ends of these doors are shown as provided with rear edge angles 3 which co-operate with angle strips 4 on the door posts to form a tight weather joint when the doors 5 are closed.

The supplemental door 2 carries, a jamb at its forward end consisting of a vertical angle 5 having one flange secured to the door with the other flange projecting inwardly and a wooden post 6 secured to the last mentioned flange. The inwardly extending flange and post 6 extend beyond the front edge of the door as shown in Figure 2 to form a lateral support for the main door 1 in its closed position. The post 6 is narrower than the end posts 7 and is brought flush therewith by a nailing strip 8 for the purpose of boarding up the doorway when it is desired to haul grain or finely divided 20 lading.

A casting 9 of angular formation is bolted or secured in any appropriate manner to the lower end of the angle bar 5. This casting is so designed that it fits within the angle of 25 the bar as shown in Figure 5. This casting is provided upon one face with a pair of spaced parallel bearing ribs or flanges 10 between which a lower detent member or cog wheel 11 and a cooperating actuating lever 12 are rotatably journaled by suitable spindles 13. The hub of the lever 12 has a plurality of cogs or teeth 14 for actuating the cog wheel 11. The cog wheel 11 cooperates with a rack plate 15 secured upon the 30 floor of the car adjacent the closing point of the doors. The rear end of the rack plate has a tooth or ridge 16 and a depression or groove 17 forward of said tooth. The forward end of the rack plate is provided with 35 a raised portion therefor 18. The inner margin of the rack plate is biased as indicated at 19. The biased position slopes inwardly in a forward direction and is undercut as shown in Figure 9 for cooperation 40 with an undercut groove 20 in an overhanging horizontal extension of one of the bearing flanges 10. The rack plate 15 is preferably anchored to the side sill of the car by bolts 21. It will be obvious that as the door 45 slides forwardly into closing position, the groove 20 will engage the biased edge of the rack plate and draw the door inwardly.

It is frequently more or less difficult to bring the door to a tight close and retain 50 it in such position. However, the above described mechanism will accomplish this. Assuming that the supplemental door has been slid forwardly until the cog wheel engages the tooth 16; if the cog wheel will not automatically rotate over said tooth into the locking position shown in Figure 8, the operator may actuate the lever 12 and rotate the cog wheel over such tooth. Then when 55 it is desired to open the door, the operator may grasp the lever 12 and elevate the same,

thereby rotating the cog wheel over the tooth 16 and starting the door towards its open position. While I have shown but a single tooth on the rack plate, it is obvious that others may be added if necessary. In the 70 position shown in Figure 8, the lever 12 locks the cog wheel 11 against rotation as will later more fully appear. From the foregoing, it will be apparent that the detent or cog wheel 11 in conjunction with the rack plate 15 and lever 12 constitute not only closing and opening mechanism for the door, but also locking mechanism therefor.

The jamb of the supplemental door is not only locked at the bottom, it is also locked 80 at the top by mechanism connected to and operable by the lever 12. To this end, a housing or casting 22 is secured upon the upper end of the angle bar 5. This casting is provided with flanges 23 and 24 bolted to 85 the flanges of the angle bar, and a flange 25 extending parallel to the flange 23. The flanges 23 and 25 are provided with bearing apertures for supporting short shafts 26 and 27. The outer margins of the flanges 23 and 25 are preferably connected by an integral web 28 which extends a short distance over the top of the casting leaving, however, a sufficient opening for a locking detent as 90 will later more fully appear.

A locking detent 29 is supported upon the shaft 27 for pivotal movement. This detent has a nose 29^a that is adapted for projection through the opening in the top of the casting for engaging an aperture 30 (Figure 10) in a stop plate 31 secured in a depression or mortise in the side plate of the doorway. This plate 31 is provided with a depending stop flange or abutment 31^a as shown in Figures 3 and 10. The lower surface of the detent slopes downwardly from the hub on the pivot shaft 27 as indicated at 32 (Figure 6). This sloping portion terminates in an abrupt head 33. A cam lever 34 is rotatably mounted intermediate its ends upon the shaft 26. This cam lever is of slightly arcuate form, and its upper end is rounded for slidably engaging the sloping surface 32 of the detent 29. In its locked position, the contacting point of the cam lever 34 with the detent 29 lies beyond the point of dead center with respect to the shaft 26, whereby they are held in locked position. It should be noted with reference to Figure 3 that a very small movement of cam lever 34 will cause the locking or unlocking of the detent 29. Consequently when the lever 12 is operated to open the door, the detent 29 will be released before the cog wheel 11 is materially actuated for opening the door. This is evident from an inspection of Figure 8. However, when the door is closed, the lever 12 is in elevated position as shown in Figure 5, so that the cam lever 34 is not brought into action with the detent until the final downward movement.

of the lever 12. Consequently, even though there is a simultaneous operation of the locking and starting mechanism, the locking detent will be released before the cog wheel is 5 materially moved for starting the door, and likewise, the door will be substantially closed before the detent 29 is elevated to locking position. A rod 35 is pivoted at its upper end in a bifurcation in the lower end of the 10 cam lever. The lower end of said rod is pivoted to the aforementioned lever 12 whereby actuation of said lever will oscillate the cam lever 34 for raising or lowering the locking detent 29. A shield 36 secured to 15 the inwardly extending flange of the angle 5 and the supplemental door encases the operating mechanism between the lower casting 9 and the upper casting 22.

In referring to Figures 3 and 4, especially 20 to the full line position of the operating mechanism, it will be observed that a tooth on the lever 12 is positioned between two teeth of the cog wheel when the same is in locking position. In this position, the detent 29 is in locking position and is retained 25 in such position as above set forth and also by the rod 35 and lever 12, the latter of which is restrained from further downward movement by the cog wheel 11 which is at 30 its forward limit of movement due to the door being closed. In such position, the supplemental door is securely locked and may form a part of the car wall when the same is used for other purposes.

If it is now desired to open the supplemental door, the operator raises the lever 12 35 into the dotted line position. This operation will oscillate the upper cam lever 34 into inoperative position as indicated in dotted lines 40 and allow the detent 29 to drop out of locking engagement with the plate 31, and at the same time this operation will rotate the cog wheel 11 over the tooth 16 into the position shown in dotted lines. This rotation of the 45 cog wheel will naturally start the door and shift the same into the dotted line position shown in Figure 4. It will hence be apparent that the door is automatically started from its closed position when unlocked.

Now assuming that the supplemental door 50 is open and it is desired to close the same; the operator will push the same to closing position. If sufficient force can be imparted 55 to the door to cause the cog wheel to rotate over the rack plate, the door will be brought to a tight close and at the same time the lever 12 will be lowered for elevating the detent 29 into locking engagement. If sufficient force cannot be imparted to the door to 60 force the cog wheel 11 over the rack plate, the operator is at liberty to actuate the lever 12 and rotate the cog wheel over the rack plate. This actuation of the lever will be 65 downward and will rotate the cam lever 34 to operative position for elevating the detent

29 to locking position. Thus the door is automatically locked as it is brought to its closing position; a single operation being only required to bring the door to a tight closed position and locking the same; likewise, only a single operation is necessary to unlock the door and start the same to open position.

It should be understood, that while I have 70 illustrated my invention in connection with a supplemental car door, it is susceptible of use on any sliding door for starting, closing and locking the same; and while I am aware that many changes may be made, and numerous details of construction may be varied 75 through a wide range without departing from the principles of this invention, I do not propose limiting the patent granted thereon otherwise than necessitated by the prior art or appended claims.

I claim as my invention:

1. In a railroad car having a main door and a supplemental door, a jamb carried by 90 said supplemental door, a lower toothed locking plate having an inclined edge, a rotatable detent member carried by said jamb for cooperating with said plate, a pivoted toothed member for actuating said detent member, means on said jamb for engaging said inclined edge for drawing the door inwardly, an upper apertured locking plate, a detent on said jamb for engaging in the aperture of said plate, operating means for said detent and a connection between 95 said operating means and said pivoted toothed member.

2. In a railway car having an extended door opening with a main door for closing a part of said opening, a supplemental door for closing the remainder of said opening, 100 said supplemental door having a jamb at its forward end, a rotatable cog wheel at the lower end of said jamb, lever mechanism for rotating and locking said cog wheel, and a rack plate upon the car sill for cooperation with said cog wheel.

3. In a railway car having an extended door opening with a main door for closing a part of said opening, a supplemental door for closing the remainder of said opening, 105 said supplemental door having a jamb at its forward edge, upper and lower locking mechanisms for said jamb, means for simultaneously operating said mechanisms, and a rack plate upon the car adapted for cooperation with one of said mechanisms for the purpose set forth.

4. In a railway car having an extended door opening with a main sliding door for closing a part of said opening, a supplemental sliding door for closing the remainder of 120 said opening, said supplemental door having a jamb at its forward edge, upper and lower locking mechanisms for said jamb, means for simultaneously operating said mecha- 125

- nisms, one of said mechanisms comprising a pair of movable members, and a rack plate cooperating with one of said members for the purpose set forth.
5. The combination with a car having a doorway with a main sliding door for closing a portion of said doorway, a supplemental sliding door for closing the remainder of said doorway, said supplemental door carrying starting and closing mechanism engageable with said car and adapted for locking said supplemental door in closed position.
6. The combination with a car having a door opening, a pair of sliding doors for closing said opening, one of said doors carrying a jamb at its forward end, interconnected locking means carried by said jamb for securing the upper and lower ends thereof, a portion of said means co-operating with the adjacent car structure for closing and opening said last mentioned door during the actuation of said means.
7. In a car having an extended door opening with a main sliding door for closing a part of said opening, a supplemental sliding door for closing the remainder of said opening, said supplemental door having a jamb at its forward end, upper and lower pivoted locking members carried by said jamb, interconnected actuatable devices for operating said members, and a stationary element co-operating with one of said members for causing a shifting movement of said supplemental door during the actuation of said devices.
8. In a car having an opening, a pair of sliding doors mounted in said opening, one of said doors having upper and lower locking members, means for simultaneously actuating said members, and a stationary rack plate for cooperation with one of said members for causing a shifting of said last mentioned door for the purpose set forth.
45. 9. In a car having a door opening, a main sliding door and a supplemental sliding door for closing said opening, a jamb on the front end of said supplemental door, a stationary rack plate having a bias portion, a depending element carried by said jamb for engaging said bias portion, a rotatable cog wheel carried by said jamb for engaging said rack plate, and a lever on said jamb having means engageable with said cog wheel for rotating the same and causing a shifting of said supplemental door, said lever serving to lock said cog wheel in a predetermined position.
10. In a car having a door opening, a main sliding door and a supplemental sliding door for closing said opening, a jamb carried by said supplemental door, a locking detent carried by one end of said jamb, a rotatable door opening and closing element carried by the other end of said jamb, a stationary rack member for cooperation with said element, and common actuatable means for operating said detent and element, said means serving to lock said element and detent when said supplemental door is closed.
11. A supplemental door for cars, said door having a jamb at its front end, a pivoted locking detent at one end of said jamb, a pivoted cam for operating said detent, a rotatable cog wheel carried by the other end of said jamb, a pivoted lever having teeth for engaging said wheel and a connection between said cam and lever whereby actuation of said lever will elevate said detent and cause said lever to interlock with said wheel.
12. In a railway car having a door opening with a main sliding door for closing a part of said opening, a supplemental door for closing the remainder of said opening, a jamb carried by said supplemental door, a pivoted locking member supported upon one end of the jamb, a rotatable cog wheel upon the other end of the jamb, a rack plate supported by the car for cooperation with said cog wheel, a pivoted lever having teeth and mounted on said jamb for actuating said cog wheel and means operated by said lever for controlling said locking member.
13. The combination with a sliding door, of starting and closing mechanism therefor comprising a rotatable cog wheel, a stationary rack plate for cooperation therewith, a pivoted toothed lever for actuating and locking said cog wheel, a pivoted locking detent, a cam lever for actuating said detent, and a connection between said cam lever and toothed lever for the purpose described.
14. The combination with a car having a door opening, of a sliding door for closing said opening, locking means for said door, starting means for said door, and an operable connection between said locking means and starting means whereby said locking means is released prior to the effective operation of said starting mechanism for opening said door.
15. The combination with a sliding door, of starting and closing mechanism therefor, and a separate locking member automatically released at the initial movement of said mechanism for opening said door.
16. The combination with a sliding door, of opening and closing mechanism therefor, and a separate locking member automatically released at the initial opening movement of said mechanism and automatically moved to locking position at the final closing movement of said mechanism.
17. The combination with a sliding door, of starting and closing mechanism therefor comprising a stationary element, a rotatable element for co-operation with said stationary element, means for operating said rotatable element, a locking member, and operating means for said locking member effec-

tive for releasing said locking member at the initial opening movement of said starting mechanism.

18. The combination with a sliding door, 5 of locking mechanism therefor, starting and closing mechanism for the door, and a connection between said starting mechanism and locking mechanism including a cam lever for releasing said locking mechanism at the 10 initial operating of starting mechanism.

19. The combination with a car having a door opening, of a door for closing said opening, starting and closing mechanism for the door, a locking member for the door, and 15 means operated by said starting and closing mechanism for releasing said locking member from locking position prior to the effective operation of said mechanism for moving said door.

20. The combination with a sliding door, 20 of starting and closing mechanism therefor comprising a rotatable cog wheel, a stationary rack plate for co-operation therewith, a toothed lever for actuating said cog wheel, a locking member, and means operated by 25 said lever for controlling said locking member.

21. The combination with a sliding door, 30 of starting and closing mechanism therefor comprising a rotatable cog wheel, a stationary rack for cooperation therewith, means for operating said cog wheel, a locking member and a connection between said means and device for controlling said locking member.

In testimony whereof I have hereunto 35 subscribed my name.

SAM F. KLOHS.
